FIREMAN'S MULTIPLE PURPOSE HAND TOOL

Jack L. Frey, American Canyon, Calif.
(2525 Fairgrounds Drive 106, Vallejo, Calif. 94590)

Filed Jan. 8, 1973, Ser. No. 321,767

Term of patent 14 years

Int. Cl. D8—03

U.S. Cl. D8—76

FIG. 1 is a perspective view of the fireman's multiple purpose hand tool.

FIG. 2 is a side elevation of the fireman's multiple purpose hand tool; the view being of the side opposite that shown in FIG. 1.

FIG. 3 is a top or upper edge plan view of the fireman's multiple purpose hand tool.

I claim:

The ornamental design for a fireman's multiple purpose hand tool, as shown.
